(57) **CLAIM**

The ornamental design for a modular holster with trigger guard, as shown and described.

DESCRIPTION

FIG. 1 is a left elevational view of a modular holster with trigger guard showing our new design.

FIG. 2 is a right elevational view thereof.

FIG. 3 is a rear elevational view thereof.

FIG. 4 is a front elevational view thereof.

FIG. 5 is a top plan view thereof; and,

FIG. 6 is a bottom plan view thereof.
